SWAGE

William Schmid, Bronson, Mich., assignor to
Harry A. Douglas, Bronson, Mich.

Application December 15, 1932, Serial No. 647,416

7 Claims. (Cl. 81—15)

This invention relates to swages.

Among other objects the invention aims to provide an improved swage embodying automatic means for limiting the pressure exertable upon the article to be swaged.

The invention is of particular utility in its embodiment, as here illustrated, in a hand tool for a swaging metallic terminal members to metallic electrical conductors, such as wires to form couplings therebetween, as disclosed in this applicant's prior copending application, Serial No. 602,912, filed April 4, 1932.

Other objects and advantages will be apparent from the following description taken in connection with the accompanying drawings in which—

Figure 1 is a partial plan view partially in section of a swage embodying the invention and being a section taken on the line 1—1 of Figure 2;

Figure 2 is a section taken on the line 2—2 of Figure 1;

Figure 3 is a view similar to Figure 1 but showing the parts in different operative position;

Figure 4 is a section taken on the line 4—4 of Figure 3;

Figure 5 is a section taken on the line 5—5 of Figure 3, parts being omitted; and

Figure 6 is a perspective view of the integral mounting ring and jaws included in my invention.

Referring in detail to the construction shown in the drawings, the illustrative tool includes an operating head 1 and operating levers 2 and 3 which are here shown for a portion of their length only, it being understood that these levers may be suitably extended to provide handles which may be conveniently gripped by one hand of the operator and to be squeezed together to actuate the operating head as presently described.

The operating head 1 desirably includes a plurality of jaws 4, in this case four which as best shown in Figure 6 are formed integral with a mounting member such as the metallic ring 5, the jaws 4 being formed as inwardly and radially extended terminations of the integral spring fingers 6 which extend axially of the ring 5. To enhance the resiliency of the fingers 6 their point of attachment to the ring 5 may be reduced as at 7. The jaws 4 form each a quarter sector of a circle described jointly by the peripheries of the fingers 6 and the pointed inner ends 8 of the jaws, which are of somewhat V shape and are desirably somewhat sharpened by

routing out the metal of the jaw on each side of the end 8 as at 8a. Thus the inner ends 8 of the jaws are directed toward, and, in the movement of the jaws later described, tend to converge at, a common axis which is also the common axis for the fingers 6 and the mounting ring 5. Also the jaws as presently described are movable in a common plane which plane is perpendicular to said axis.

To effect the movement of the jaws referred to, the spring fingers 6 are provided with cam surfaces 10 tapering toward their free terminations and adjacent the jaws 4.

The mounting ring 5 with the fingers 6 integral therewith is here shown received in a cylindrical housing 11 having an end wall 12 and a circular aperture 13 in this end wall through which the tapered terminations of the fingers 6 are adapted to pass. The margins of the circular aperture 13 are desirably also tapered as at 14 to conform somewhat to the tapered surfaces 10 of the fingers and to ride upon these surfaces in engagement therewith as the terminations of the fingers are forced through the aperture 13 to move the jaws 4 together centripetally as presently described.

To effect relative movement of the fingers 6 and the housing 11 just referred to, the mounting ring 5, in this instance, receives therethrough a spring barrel 15 which has an annularly flanged outer end 16 axially abutting the mounting ring 5, upon its side opposite the aperture 13, through the intermediation of a metallic washer 17. To prevent rotation of the washer 17 and spring barrel 15 with respect to the housing 11 the housing is desirably slotted at diametrically opposite sides as at 18. Ears 19 and 20, respectively, on the washer 17 and flange 16 of the spring barrel are also diametrically oppositely located to be received in the slots 18 which are elongated transversely of the housing to permit the parts to move axially therein as described. The slots 18 also merge into the open end 21 of the housing, so that the mounting ring with its integral fingers, the washer 17 and the spring barrel 15 may be readily inserted through this open end with the ears located in the slots.

The levers 2 and 3 are pivoted to the housing 11 as at 22 and 23, respectively, the housing at this point being desirably radially enlarged as at 24, in two spaced apart somewhat semi-circular segments 24, 24a to provide bearings for the levers 2 and 3 and to accommodate the pins 25 upon which the levers are pivoted, these pins being passed through countersunk recesses 26 in 55

the segment 24 and being threadedly received as at 27 in threaded passages in the segment 24a. Thus the pins 25 are advantageously protected by the peripheries of the segments 24 and 24a. 5 In addition to being diametrically oppositely pivotedly connected to the housing 11, as described, the levers 2 and 3 have inwardly directed extensions 28, 28a, respectively, which are fulcrumed in the spring barrel 15. In this instance, these extensions 28, 28a are fulcrumed 10 on a plate 29 which is housed within the spring barrel 15, the plate 29 being somewhat larger than the main body of the spring barrel, but being received in the hollow annular flange 16 15 thereof. The relative proportions of the flange 16 and plate 29 are such that the plate may have restricted movement axially of the spring barrel which movement is opposed by a relatively heavy coil spring 30 also housed within the spring barrel 20 15. Thus when the levers 2 and 3 are squeezed together from the position shown in Figure 1 to the position shown in Figure 3, the levers being fulcrumed by their extensions upon the plate 29 and being pivoted to the housing 11 tend to 25 move the housing and plate relatively in an axial direction. Until the spring 30 yields, the plate 29 being at this time fixed with respect to the spring barrel 15 moves with the spring barrel itself, and, through the intermediation of 30 the spring barrel, moves the mounting ring 5. Relative axial movement of the mounting ring 5 and housing 11 thus effected forces the tapered terminations of the spring fingers through the aperture 13 and forces the jaws 4 together, the 35 extent of movement of the jaws centripetally being determined by the relative longitudinal movement of the tapered surfaces 10 and 14.

Movement of the jaws 4 as described may be employed to couple together the metallic terminal 31 and wire 32 in the bore thereof, the V-shaped inner ends 8 of the jaws indenting the terminal 31 as at 33, reducing the bore of the terminal member as at 34, and distorting the wire 32 to provide interengaging shoulders 45 between the wire and bore of the terminal which securely couple the wire and terminal together.

To limit the pressure which may be placed upon the terminal 31 to that necessary to form the above described coupling, I desirably provide 50 yieldable means for limiting further movement of the mounting ring 5 within the housing 11. As best shown in Figure 3 when a predetermined pressure proportional to the resistance encountered by the jaws has been placed upon the terminal 31, the spring 30 yields and the plate 29 acts as a plunger which follows the spring and permits the fulcrum point of the extensions 28, 28a to move. This stops relative movement of the housing 11 and mounting ring 5, which, in 55 turn, stops further movement of the jaws 4 inwardly, provided the plate 29 has not traveled the full extent of its possible axial movement with respect to the spring barrel 15. I provide means for regulating the movement of the plate 29 to suit the pressure desired to be exerted by the jaws 4 and for this purpose, I make the inner end of the spring barrel 15 in the form of a movable plug 35 which is threadedly received in the spring barrel and which, by means of a shank 36 passing freely outwardly through the 60 spring, spring barrel and plate 29, may be adjusted to regulate the pressure of the spring 30 upon the plate 29. The shank 36 may have its outer end slotted as at 37 to be turned by a 65 screw-driver and the extensions 28, 28a of the 70

levers 2 and 3 may be offset upon each side of this shank as best shown in Figure 2.

When the levers have been moved together to move the parts of the operating head to the position shown in Figure 3 and the levers are released, the resiliency of the fingers 6 moves the housing 11 and the mounting ring 5 in the opposite direction to restore the parts to the position shown in Figure 1. To limit movement of the levers 2 and 3 apart they may be provided 10 with stops 38 and 39, respectively, which abut the housing 11 in the separated position of the levers as shown in Figure 1.

To limit extent of insertion of the terminal 31 between the jaws 4, I provide a gauge 40 which 15 may be of cylindrical form and may be slipped over the housing 11. The ears 19 of the washer 17 may be extended beyond the housing 11 to engage an annular slot 41 in the gauge 40, this slot meeting diametrically opposite transverse 20 slots 42 which merge into the slot 41 and open into the outer end of the gauge, so that the ears 19 may be passed through the diametrically opposite slots 42 and then by a rotation of the gauge be received in the slot 41 to secure the 25 gauge slidably to the housing 11, the gauge sliding on the housing 11 in response to movement of the mounting ring 5 and spring barrel 15. The gauge may have an end wall 42a apertured as at 43 concentrically with the common axis 30 of the parts and this aperture may be tapered to correspond with the taper of the terminal 31 and thus limit insertion of the tapered terminal into the aperture 43 to a point where the terminal 31 is in engagement with the jaws 4 near 35 its extremity as shown in Figures 1 and 3.

Having described an embodiment of my invention, I claim:

1. In a swage, the combination of a plurality of jaws arranged about a common center and radially reciprocable; resilient supports for said jaws; cam surfaces on said supports; a mounting for said supports; a member movable relatively to said supports and mounting and engageable with said surfaces to move said jaws, 45 said jaws moving radially inwardly against the resiliency of the supports upon movement of the member in one direction and moving radially outwardly upon movement of the member in the opposite direction; means for moving the member and yielding means interposed between the movable member and the moving means therefore operative upon the jaws encountering a predetermined resistance.

2. In a swage, the combination of a metallic 55 mounting ring; a plurality of spring fingers extending axially of said ring, the terminations of said fingers being turned toward the axis of the ring to provide radially movable jaws and said fingers having surfaces tapering toward said terminations; a cylindrical housing for said ring having an apertured wall at one end, said aperture receiving the fingers therethrough and said wall being engageable with the tapered surfaces; means for causing relative movement of the ring and housing to force the fingers through said aperture to cause the housing to contract the fingers and move the jaws together and yielding means interposed between the moving means and ring actuated upon the jaws encountering a 60 predetermined resistance to prevent further relative movement thereafter of the ring and housing.

3. In a swage, the combination of a metallic 65 mounting ring; a plurality of spring fingers ex- 70

5 tending axially of said ring, the terminations of
said fingers being turned toward the axis of the
ring to provide radially movable jaws and said
fingers having surfaces tapering toward said
terminations; a cylindrical housing for said ring
10 having an apertured wall at one end, said aperture
receiving the fingers therethrough and said
wall being engageable with the tapered surfaces;
means for causing relative movement of the ring
15 and housing to force the fingers through said
aperture to cause the housing to contract the
fingers and move the jaws together and yielding
means interposed between the moving means
20 and ring actuated upon the jaws encountering
a predetermined resistance to prevent further
relative movement thereafter of the ring and
housing.

25 4. In a swage, the combination of a metallic
mounting ring; four integral spring fingers ex-
tending axially of said ring, the terminations of
said fingers being turned toward the axis
of the ring to provide radially movable jaws in
a substantially common plane and said fingers
adjacent the terminations having surfaces ta-
pering toward said terminations; a cylindrical
housing for said ring receiving said ring, said
housing having an apertured wall at its end
adjacent the terminations, said aperture receiv-

5 ing the terminations therethrough and said wall
engaging the said tapered surfaces, said aper-
ture being circular and the peripheries of said
fingers jointly describing a circle; a spring bar-
rel received between said fingers in abutment
with said ring upon its side opposite said aper-
ture; a plunger having limited movement in said
barrel; a spring in said barrel pressing said
plunger outwardly thereof; and a pair of levers
10 pivoted on said housing and fulcrumed on said
plunger.

15 5. The structure of claim 4 wherein the end
of the spring barrel opposite the plunger is ad-
justable to control the pressure of the spring
on the plunger.

15 6. The structure of claim 4 wherein a washer
is interposed between the ring and the barrel
and said washer and barrel carry diametrically
opposite aligned projections and said housing
is slotted to permit said projections to move
20 therein.

25 7. The structure of claim 4 wherein a cylin-
drical gauge member is passed over said housing
and secured thereto, said gauge member having
a wall adjacent the end wall of the housing and
a hole therein concentric with the common axis
of the jaws.

WILLIAM SCHMID.
